ABSTRACT OF THE DISCLOSURE

A sewing machine needle of the hollow type formed from a blank of sheet metal having an edge configuration designed to provide for the formation of the essential characteristics of a needle, so that the blank when rolled forms a hollow needle which satisfactorily will sew in a standard sewing machine.

The present invention relates to the art of sewing machines and more particularly to a hollow needle adapted for use in a sewing machine and a method of forming such a needle.

In order to provide a hollow needle that will sew satisfactorily it is necessary that the needle withstand machine sewing abuse. The design of the hollow needle must be such that it will not fray the thread or material fibers. Also, the thread freely must flow so that it will not bind as the needle carries the thread through materials being sewn. In addition to these characteristics, the needle point readily must penetrate the material being sewn and the needle eye has to be properly oriented to perform proper machine sewing.

The present invention accomplishes the above and more by providing a hollow needle comprising an elongated sheet metal blank member with an edge configuration which provides for the formation of an eye, a point, thread clearance, etc., which structure is obtained when the needle is roll-formed from the sheet metal. The blank member is die-cut to the desired size and is provided at one end with a pair of tapered points which, when roll-formed, form a conical point with its apex at the centerline of the needle. The side edges disposed in proximity to said one end of said member are designed to have a configuration such that when the blank is rolled portions of the edges will overlap to form an aperture or needle eye. One of the embodiments of the present invention comprises an easy-threading type hollow needle wherein the overlapping portion of the side edges is sufficiently open to allow for thread entry by wiping the thread along the side of the needle into the needle eye.

Accordingly, it is a primary object of the present invention to provide a hollow sewing machine needle that is relatively simple in construction and inexpensive to make.

Another object of the present invention is to provide a hollow needle which can withstand sewing machine abuse and will not cause damage to the material being sewn.

A further object of the present invention is to provide a hollow needle that easily can be threaded.

A still further object of this invention is to provide a hollow needle that will sew properly and duplicate the various functions of conventional needles.

Having in mind the above and other objects that will be evident from an understanding of the disclosure, the invention comprises the combination and arrangement of structure as illustrated in the presently preferred embodiments of the invention, which is hereinafter set forth in such detail as to enable those skilled in the art readily to understand the function, operation, construction and

2

advantages of it when read in conjunction with the accompanying drawings in which:

BRIEF DESCRIPTION OF THE DRAWINGS

FIG. 1 is a plan view of a lower portion of an elongated sheet metal blank member having the necessary edge configuration required to form a hollow needle according to the present invention;

FIG. 2 is a partial elevational view of the blank member of FIG. 1 rolled to form a hollow needle according to the present invention;

FIG. 3 is a sectional view taken substantially through the line 3—3 of FIG. 2 showing an easy-threading type hollow needle;

FIG. 3A is a sectional view substantially similar to FIG. 3 illustrating a roll-formed needle of the non-easy-threading type;

FIG. 4 is a plan view similar to FIG. 1, but of another embodiment of the present invention comprising a hollow needle;

FIG. 5 is a partial elevational view of the blank member of FIG. 4 rolled to form a hollow needle according to the present invention;

FIG. 6 is a sectional view taken substantially through the line 6—6 of FIG. 5 showing the needle designed for easy-threading.

DESCRIPTION OF THE PREFERRED EMBODIMENTS

Referring more specifically to the drawings and in particular to FIGS. 1 and 2, there is disclosed a hollow needle generally designated 11 roll-formed from an elongated substantially flat metal blank member 12, which is cut to the desired size from a piece of sheet metal having an inner surface 13. It is to be understood that although the shank portion of the hollow needle is not fully illustrated, this part of the needle is designed so that the needle may not be inserted and operably held in a needle clamp (not shown) on a standard sewing machine.

The metal blank 12 has a certain edge configuration disposed at an extremity 15 thereof, more appropriately defined as the needle point portion. This edge configuration is designed to provide the necessary shapes for roll-forming a hollow needle. In the illustration given the hollow needle 11 is cylindrical in shape with a lumen 44 extending longitudinally therethrough and a needle point 42 formed at one end. The hollow conical-shaped needle point 42 is formed by the edge configuration comprising a pair of V-shaped tapered points 16 and 17, respectively formed by sloping edges 18, 19 and 20, 21. The edges 18 and 19 and 20 and 21 slope downward towards each other as shown in FIG. 1, respectively to form the tapered points 16 and 17. The inner sides 18 and 20 in turn define an inverted V-shaped cutout designated at 22.

The side edges of the metal blank 12 each are provided with an outwardly extending protrusion designated generally by reference numerals 23 and 24, which provide for formation of a needle eye 41 (FIG. 2). The protrusion 23, which is complementary to and is disposed external of protrusion 24 when the hollow needle 11 is formed (see FIG. 2), comprises a pair of similar oppositely sloped shoulder members 25, 26. These shoulders, which are rounded so as not to fray the thread or the material fibers, define a substantially T-shaped cutout area including a channel portion 29 formed by the extremities of the said shoulders and an elongated eye-forming area 31. The channel 29 extends inward toward the blank 12 into the elongated cutout area 31 whose long diameter is disposed parallel to the longitudinal axis of the needle 11. The remainder of the cutout area 31

is defined by an inner downward sloping edge 35 of the shoulder 26, and a longitudinally disposed edge 36 of the blank 12 disposed between the shoulders 25 and 26, and in substantially the same plane as an edge portion of the blank 12 disposed above an outer downward sloping edge 34 of the shoulder 25. The upper portion of the edge 19 of the tapered point 16 defines the outer edge of the shoulder 25. Formed on the shoulders 25 and 26 are a pair of indentations 27 and 27' provided above and below the needle eye 41, respectively, for simulating the groove provided in a conventional needle. These indentations, when disposed as shown in FIG. 2, permit free flow of the thread as the needle penetrates the material. As shown in FIG. 1, the indentations are raised relative to the surface 13 of the metal blank 12, that is, they extend toward the person viewing this figure. The protrusion 24, which is disposed on the edge of the blank 12 opposite protrusion 23, comprises an edge configuration including a lower rounded shoulder 28 and a vertical edge of the blank 12 terminating in a curved inner edge 37. The upper portion of the edge 21 of the tapered point 17 forms the outer edge of the lower shoulder 28, while the inner edge thereof is defined by an upward sloping edge 39. The rounded extremity of the shoulder 28 with the lower portion of the vertical edge substantially define a channel 30 which leads into an elongated cutout area 32 having an innermost edge 43 which is substantially similar to the elongated area 31 disposed on the opposite side of the blank 12. The cutout areas 31 and 32 are designed so that when the blank 12 is roll-formed into the needle 11, as shown in FIG. 2, a needle eye 41 is formed on one surface thereof wherein the edges 36 and 43 longitudinally define the sides of the needle eye and the inner edges of the shoulders 25, 26 and 28 and the edge 37 effectively define the respective upper and lower sides of the needle eye. The edge configuration comprising the protrusion 24 is formed on an offset portion 40 of the sheet metal member, which is raised relative to the inner surface 13 of the blank 12 and is indented relative to the outer surface 14 (FIG. 2) of the member. Also forming part of the edge configuration are a pair of indented portions 38 and 38' which are raised relative to the offset portion 40 in FIG. 1. These portions form a receptacle for the portions 27 and 27' respectively, as best shown in FIG. 2, thereby simulating the conventional needle groove. A part of the outer surface of the offset portion 40 is disposed below the shoulders 25, 26 when the needle is roll-formed as shown in FIG. 2. The shoulder 28 is disposed adjacent the edge 36 on the inner surface 13 of the blank member 12. This arrangement reinforces the metal thickness around the needle eye thereby substantially strengthening this part of the needle 11. It should be noted that the vertical edge from which the curved edge 37 depends does not continue beyond the center line of the needle eye, otherwise, the thread could not properly enter the needle eye 41.

FIG. 3 shows an embodiment of the needle of FIGS. 1 and 2 comprising a hollow needle of the easy-threading type. As shown, the overlapping shoulders 25, 26 sufficiently are spaced from the offset portion 40 to allow for easy threading of the needle merely by wiping the thread T along the outer surface 14 of the needle 11 into the eye 41. The thread is then longitudinally disposed in the lumen or bore 44 of the hollow needle 11, FIG. 2, while the top part thereof is secured to a thread supply (not shown).

FIG. 3A shows another embodiment of a hollow needle which is not of the easy-threading type. As shown, the overlapping shoulders 25, 26 are disposed contiguous to the outer surface of the indented portion 40. Thus, threading of the needle is relatively more difficult since there is no opening as in the embodiment of FIG. 3 through which the thread may be passed to enter the needle eye 41.

41. In the embodiment shown in FIG. 3A, the needle may be threaded by using a wire-type threading device. By attaching the thread from the thread supply to one end of such a device the operator may then proceed to thread the needle from the shank to the needle eye by inserting the wire into the bore 44 of the hollow needle and drawing it through the needle eye 41 with the thread attached thereto.

FIGS. 4, 5 and 6 illustrate a third embodiment of the invention comprising an easy-threading hollow needle 51 roll-formed from a sheet metal blank 52 having the necessary edge configuration disposed within a needle point portion 55 to form a conical-shaped tapered needle point 75, a longitudinally defined bore 76 and a needle eye 74. The blank has an inner surface 53 and an outer surface 54. The needle point is formed in a manner similar to the point 42 in the preceding embodiment by a pair of tapered points 56, 57 respectively defined by a pair of edges 58, 59 and 60, 61. The points are constructed and arranged so that they define an inverted V-shaped cutout area 62 between the edges 58, 60 whereby when the blank is roll-formed into the needle 51 shown in FIG. 5 the tapered points overlap to form the needle point 75. The edge configuration of the needle point portion 55 is formed substantially similar to that shown in FIG. 1. However, the edge 61 of the tapered point 57, which corresponds to the edge 21 in FIG. 1, is abruptly terminated by an oppositely sloping edge 70 as shown in FIG. 4. The edge 61 preferably is terminated in this manner, rather than extend further upward, to facilitate threading of the needle eye 74. An L-shaped shoulder member 63 is formed in proximity to and above the tapered point 57. This shoulder member, which facilitates easy threading of the needle eye 74, comprises a round elongated cantilever member 64 and a supporting member 65 disposed substantially perpendicular to said cantilever member. The member 64 is integrally formed, with the blank 53 and the member 65. An inner edge 68 of the cantilever member of the shoulder 63 and an edge 67 of the blank define a round elongated opening 66 which forms the needle eye 74 illustrated in FIG. 5. An upper and lower portion 78 and 78' which are raised relative to the surface 53 of the blank as shown in FIG. 4, simulate a conventional needle groove or channel when roll-formed into the needle shown in FIG. 5. A space or channel like area 69, which essentially is defined by the edge 70 and the inner lower rounded portion of the member 64, is located so that when the blank is rolled to form the hollow needle, the operator readily can thread the needle eye by wiping the thread along the needle surface 54 under the shoulder 63 into the eye 74. Along the edge of the blank opposite the shoulder 63 is formed a notched-out portion 71 comprising a shelf-like edge 73 and a vertical edge 72. This portion is arranged so that the edge 72 substantially coincides with the inner edge 68 of the cantilever member 64, as best shown in FIG. 4, to form one side of the elongated needle eye 74, while the edge 67 of the blank forms the other edge of the needle eye. A portion 77 raised relative to the surface 53 is formed adjacent the shelf-like edge 73 for receiving the portion 78' therein when the needle is roll-formed as shown in FIG. 5 to form the needle groove. Thus, it is seen that the edge configuration formed at 71 substantially is complementary to the configuration defined by shoulder 63 to enable formation of the needle eye. The member 64 overlaps the edge 72 and preferably is spaced from the outer surface 54 (see FIG. 6) of the hollow needle 51 to allow for easy threading of the needle.

It is to be understood that although the needle shown in FIG. 5 is of the easy-threading type, it also can be formed with the cantilever member 64 flush against the outer surface 54 of the needle, whereby threading would be accomplished in substantially the same manner as for

the hollow needle shown in FIG. 3A. Also, although the edges of the partially illustrated shank portion of the needles have been shown to define a longitudinal opening (FIGS. 2 and 5) disposed above the needle eye, it is to be understood that the design of the hollow needle may be such that these edges will be roll-formed into substantial abutting relation thereby eliminating this opening.

Numerous alterations of the structure herein disclosed will suggest themselves to those skilled in the art. However, it is to be understood that the present disclosure relates to a preferred embodiment of my invention which is for purposes of illustration only and not to be construed as a limitation of the invention. All such modifications which do not depart from the spirit of the invention are intended to be included therein.

Having thus set forth the nature of my invention, what I claim is:

1. A hollow needle having a needle point and a needle eye adapted for use in a sewing machine, comprising an elongated rolled metal blank member having at least a first longitudinal extending edge and formed at an extremity thereof with a pair of overlapping needle point forming members defining the needle point of said hollow needle, protruding means disposed on the first edge of the rolled member and forming with a complementary portion of the rolled member a thread-receiving aperture in the surface of said hollow needle, said rolled metal blank member being constructed and arranged so that said thread-receiving aperture comprises the needle eye of said hollow needle and simultaneously is formed with said needle point. 30

2. A hollow needle according to claim 1 wherein each of the needle point forming members comprises a tapered configuration thereby to define a conically-shaped needle point.

3. A hollow needle according to claim 1 wherein the

rolled member has a second longitudinal extending edge disposed opposite the first edge, an edge configuration including said protruding means formed on at least said first edge and forming therewith an elongated opening that is disposed proximate the second edge thereby to define said needle eye.

4. A hollow needle according to claim 1 wherein the rolled member includes a second longitudinal extending edge disposed opposite the first edge and each of the longitudinal edges includes an edge configuration constructed and arranged to define said needle point and said needle eye. 10

5. A hollow needle according to claim 4 wherein at least one of said edge configurations includes a shoulder extending therefrom and overlapping a predetermined portion of the other edge configuration. 15

6. A hollow needle according to claim 5 wherein the overlapping shoulder sufficiently is spaced from the proximate outer surface of the other edge configuration whereby threading of the needle is facilitated. 20

7. A hollow needle according to claim 5 wherein the overlapping shoulder is disposed contiguous to the proximate outer surface portion of said other edge configuration. 25

8. A hollow needle according to claim 4 wherein one of said edge configurations is formed on a surface portion of the rolled member offset relative to the surface adjacent thereto. 30
